TIME DELAY FUSE

Edward V. Sundt, Wilmette, Ill., assignor to Sundt Engineering Company, Des Plaines, Ill., a corporation of Illinois

Application April 28, 1954, Serial No. 426,077

14 Claims. (Cl. 200—123)

The principal object of this invention is to provide an improved time delay fuse for electric circuits which provides substantially instantaneous action upon the occurrence of high overloads, which provides a time delayed action upon lower sustained overloads, which prevents needless fuse blowing on harmless overloads, which utilizes a new and improved principle of operation, which is of a new and improved construction, which is fool-proof in operation, and which can be inexpensively manufactured.

Basically, the time delay fuse of this invention is a heat operated device wherein heat is generated therein through the passage of electric current and absorbed over time up to a calibrated point of fusion in order to secure the desired delay. Two physical factors are utilized to secure the time delay, the specific heat of the entire fuse element and the latent heat of fusion of a body of fusible metal purposely added to the element.

Briefly, the time delay fuse of this invention includes an electrically conductive fuse element formed from a fusible metal and having between its ends a receptacle portion and a resistance heating portion of limited cross sectional area adjacent the receptacle portion. A body of fusible metal of lower melting point than that of the fuse element is secured in the receptacle portion of the fuse element in intimate contact therewith so as to provide high thermal conductivity therebetween. Electrical terminals are connected to the ends of the fuse element for incorporating the same in an electric circuit to be protected.

A sustained overload in the electric circuit causes the resistance heating portion of the fuse element to heat the fuse element and the body of fusible metal substantially as a unit. The heating of the resistance heating portion of the fuse element to the melting point thereof for breaking the electric circuit being protected is delayed by the specific heat and the latent heat of fusion of the body of fusible metal. In this way substantial time delays in blowing of the fuse at the resistance heating portion thereof may be obtained. At the same time a high overload, such as caused by a short circuit, will substantially instantaneously blow the fuse at the resistance heating portion thereof.

Preferably, the fuse element of the time delay fuse of this invention includes a pair of spaced apart receptacle portions provided with the lower melting point fusible metal in each, an inner resistance heating portion extending therebetween and an outer resistance heating portion extending outwardly from each receptacle portion. Here, the delayed blowing of the fuse normally takes place at the inner resistance heating portion, where blowing conditions may be more readily calibrated and controlled, while instantaneous blowing may take place at any one or more of the three resistance heating portions. The fuse element may be encased in a tubular closure of electrical insulating material provided with metallic end

2

caps to which the ends of the fuse element are electrically connected to form a cartridge type of fuse. Of course, other types of closures may be utilized.

The fuse element may be formed from a sheet of fusible metal and the receptacle portions may be substantially tubular in shape formed by suitably stamping and bending the sheet. The bodies of fusible metal may be secured in the tubular receptacle portions merely by dipping the fuse element in a molten pool of the lower melting point fusible metal. Substantially any kind of fusible metals may be used for the fuse element and the fusible bodies depending upon the fusing conditions to be met. They may be basic metals or alloys of metals, eutectic alloys being preferred for the lower melting point fusible bodies since their melting conditions may be more readily determined and calibrated. Preferably, the outer resistance heating portions of the fuse element are bent substantially normal to the axes of the cylindrical receptacle portions to compensate for thermal expansion and contraction.

Other objects of this invention reside in the details of construction of the time delay fuse and in the cooperative relationships between the component parts thereof.

Other objects and advantages of this invention will become apparent to those skilled in the art upon reference to the accompanying specification, claims and drawings in which:

Fig. 1 is a perspective view of a time delay fuse constructed in accordance with this invention;

Fig. 2 is a sectional view taken substantially along the line 2—2 of Fig. 1;

Fig. 3 is one form of a blank formed from a sheet of fusible metal from which the fuse element is fabricated;

Fig. 4 is another view similar to Fig. 3 showing another form of blank for fabricating the fuse element;

Fig. 5 is a perspective view of a fuse element formed into shape and including the bodies of fusible metal;

Fig. 6 is a sectional view taken substantially along the line 6—6 of Fig. 2;

Fig. 7 is a sectional view taken substantially along the line 7—7 of Fig. 2.

The time delay fuse of this invention is generally designated at 10. It includes a fuse element 11 formed from a sheet of fusible metal. The blank from which the fuse element is fabricated is illustrated in Fig. 3. It includes a pair of parts 12 and 13 which ultimately form the substantially tubular cavities. Extending between the parts 12 and 13 is a resistance heating portion 14 of limited cross sectional area. As illustrated the part 14 is provided with a cut-out 15 to limit the cross sectional area. When current is passed through the fuse element 11 the portion 14 of limited cross sectional area is heated thereby. Extending from the outer end of each part 12 and 13 is a tab 16 and a tab 17, respectively. These tabs 16 and 17 are provided with cut-outs 18 and 19 for providing the tabs with a limited cross sectional area so that the tabs 16 and 17 also form resistance heating portions of the fuse element 11. As shown in Fig. 4 the tabs 16 and 17 may be made narrower to provide resistance heating portions of limited cross sectional area.

In fabricating the fuse element the parts 12 and 13 are formed into substantially cylindrical cavities as illustrated in Fig. 5. The tabs 16 and 17 adjacent the outer ends of the receptacle portions 12 and 13 are bent substantially normal to the axes of the receptacle portions as shown in Fig. 5. After the fuse element has been so formed or fabricated, it is then first dipped in a flux and immediately thereafter into a molten pool of fusible metal of lower melting point. In so doing, the fusible metal flows into the tubular receptacles 12 and 13 and is maintained in

there by capillary attraction. When the fuse element is removed from the molten pool, the fusible metal solidifies in the receptacle portions and is thereby permanently secured therein in intimate contact therewith so as to provide high thermal conductivity therebetween. The fuse element is then provided with a rinse to remove excess flux and it is then ready for incorporation into a suitable closure.

The closure for the fuse element may include a tubular closure 25 formed of electrical insulating material such as glass or the like. The ends of the tubular closure 25 are preferably turned inwardly slightly as indicated at 26 and 27. The fuse element is inserted in the closure 25 and metallic end caps 28 and 29 are placed over the ends of the closure 25. The end caps 28 and 29 are secured in place on the tubular closure 25 and are electrically connected to the ends of the fuse element 11 by means of solder indicated at 30 and 31. The end caps 28 and 29 therefore provide electrical connections for connecting the fuse of this invention into an electrical circuit to be protected.

When a sustained overload occurs in the electric circuit, it causes the resistance heating portions 14, 16 and 17 of limited cross sectional area to heat the fuse element 11 and the bodies of fusible metal 22 and 23 substantially as a unit. The heating of the resistance heating portions of the fuse element to the melting point thereof for breaking the electric circuit being protected is delayed by the specific heat of the unit as a whole and the latent heat of fusion of the bodies of the fusible metal. In this way substantial time delays in blowing of the fuse at the resistance heating portions thereof may be obtained. Since the resistance heating portion 14 is located between the bodies of fusible metal 22 and 23 and will probably be of higher temperature than the other resistance heating portions 16 and 17, the fuse will blow on sustained overload conditions at this point rather than the other two points. At the same time a high overload condition such as caused by a short circuit will substantially instantaneously blow the fuse at any one or more of the resistance heating portions 14, 16 and 17. Because the resistance heating portions 16 and 17 are bent substantially normal to the axis of the cylindrical receptacle portions 12 and 13, these bent portions may flex upon expansion and contraction of the fuse element due to temperature conditions and therefore the fuse of this invention is fully compensated for thermal expansion and contraction and fatiguing of the fuse element is maintained at a minimum.

Substantially any kind of fusible metals may be used, depending upon the fusing conditions to be met. For example, the fuse element 11 may be formed from sheet zinc or the like. Different ampere ratings of the fuse element may be obtained by varying the thickness of the zinc sheet and in practical application this ranges from .0015 to .015 inch for small fuses. Accordingly this design provides an inexpensive means for securing a great number of ampere, or intermediate ampere, ratings. In regard to the melting points of the fusible metal bodies 22 and 23 it is preferable not to have the melting point much lower than 288° F., which is the eutectic of tin and bismuth, nor is it desirable to have the maximum more than 690° F., which is the eutectic of cadmium and silver. The eutectic of tin and lead, melting at approximately 360° F., is a good compromise temperature, and is high enough above normal ambient temperatures so that the blowing characteristics of the fuses are not influenced greatly thereby.

In service under operating conditions, the assembled fuse of this invention will carry 110% of rated current for a minimum of four hours. If the current is increased to any value from about 135% of rating and up to less than 400% of rating, the resistance heating portions of the fuse element generate enough heat to bring the fusible metal in the heat receptacles up to the melting point

thereof. Up to this point, delay in fuse action is due principally to the specific heat of the fuse element and the bodies of fusible metal. Above this point, the fusion metal is changed from solid to liquid, and no further temperature rise takes place until all of the fusible metal has changed state, and a further delay is thus obtained due to the latent heat of fusion. Depending on the alloy used in the bodies of fusible metal, this delay is several times that obtained by the specific heat only. At 135% of rating, the fuse of this invention will blow in about one hour's time while at 400% rating, the fuse will blow in about five second's time. Above 400% rating, the fuse will blow at a time inversely proportional to the over-load.

While for purposes of illustration one basic form of this invention has been disclosed, other forms thereof may become apparent to those skilled in the art upon reference to this disclosure and therefore this invention is to be limited only by the scope of the appended claims.

I claim as my invention:

1. A time delay fuse comprising an electrically conductive single piece fuse element formed from a fusible metal having a predetermined relatively high melting point and having between its ends a receptacle portion 25 and a resistance heating portion of limited cross sectional area at each end of and adjacent to the receptacle portion, a body of fusible metal having a predetermined relatively low melting point and secured in the receptacle portion of the fuse element in intimate contact therewith so as to provide a high thermal conductivity therebetween, and electrical terminals connected to the ends of the fuse element for incorporating the same in an electric circuit to be protected, a sustained overload in the electric circuit causing the resistance heating portions of the fuse element 30 to heat the fuse element and the body of fusible metal substantially as a unit, and the heating of the resistance heating portions of the fuse element to the relatively high melting point thereof for breaking the electric circuit being delayed by the specific heat and the latent heat of fusion of the body of the relatively low melting point fusible metal.

2. A time delay fuse comprising an electrically conductive elongated single piece fuse element formed from a fusible metal having a predetermined relatively high melting point and having between its ends a pair of spaced apart receptacle portions, a resistance heating portion of limited cross sectional area adjacent to and between the receptacle portions and a resistance heating portion at and adjacent to the outer end of each receptacle portion, a body of fusible metal having a predetermined relatively low melting point and secured in each receptacle portion of the fuse element in intimate contact therewith so as to provide high thermal conductivity therebetween, and electrical terminals connected to the ends of the fuse element 45 for incorporating the same in an electric circuit to be protected, a sustained overload in the electric circuit causing the resistance heating portions of the fuse element to heat the fuse element and the bodies of fusible metal substantially as a unit, and the heating of the resistance heating portions of the fuse element to the relatively high melting point thereof for breaking the electric circuit being delayed by the specific heat and latent heat of fusion of the bodies of the relatively low melting point fusible metal.

3. A time delay fuse comprising an electrically conductive elongated single piece fuse element formed from a sheet of fusible metal having a predetermined relatively high melting point and having between its ends a substantially tubular part forming a receptacle portion and a tab of limited cross sectional area extending from each end of the tubular part and each forming a resistance heating portion adjacent to the receptacle portion, a body of fusible metal having a predetermined relatively low melting point and secured in the receptacle portion of the fuse element in intimate contact therewith so as to provide high thermal conductivity therebetween, and electrical

terminals connected to the ends of the fuse element for incorporating the same in an electric circuit to be protected, a sustained overload in the electric circuit causing the resistance heating portion of the fuse element to heat the fuse element and the body of fusible metal substantially as a unit, and the heating of the resistance heating portions of the fuse element to the relatively high melting point thereof for breaking the electric circuit being delayed by the specific heat and the latent heat of fusion of the body of the relatively low melting point fusible metal.

4. A time delay fuse comprising an electrically conductive elongated single piece fuse element formed from a sheet of fusible metal having a predetermined relatively high melting point and having between its ends a substantially tubular part forming a receptacle portion and a tab of limited cross sectional area extending from each end of the tubular part and each forming a resistance heating portion adjacent to the receptacle portion, a body of fusible metal having a predetermined relatively low melting point and secured in the receptacle portion of the fuse element in intimate contact therewith by dipping the fuse element in a molten pool of said lower melting point fusible metal so as to provide high thermal conductivity therebetween, and electrical terminals connected to the ends of the fuse element for incorporating the same in an electric circuit to be protected, a sustained overload in the electric circuit causing the resistance heating portion of the fuse element to heat the fuse element and the body of fusible metal substantially as a unit, and the heating of the resistance heating portions of the fuse element to the relatively high melting point thereof for breaking the electric circuit being delayed by the specific heat and the latent heat of fusion of the body of the relatively low melting point fusible metal.

5. A time delay fuse comprising an electrically conductive elongated single piece fuse element formed from a sheet of fusible metal having a predetermined relatively high melting point and having between its ends a pair of spaced apart substantially tubular parts forming a pair of spaced apart receptacle portions, a part of limited cross sectional area extending between the tubular parts and forming a resistance heating portion adjacent to and between the receptacle portions, and a tab of limited cross sectional area extending from the outer end of each tubular part and each forming a resistance heating portion at and adjacent to the outer end of each receptacle portion, a body of fusible metal having a predetermined relatively low melting point and secured in each receptacle portion of the fuse element in intimate contact therewith so as to provide high thermal conductivity therebetween, and electrical terminals connected to the ends of the fuse element for incorporating the same in an electric circuit to be protected, a sustained overload in the electric circuit causing the resistance heating portions of the fuse element to heat the fuse element and the bodies of fusible metal substantially as a unit, and the heating of the resistance heating portions of the fuse element to the relatively high melting point thereof for breaking the electric circuit being delayed by the specific heat and latent heat of fusion of the bodies of the relatively low melting point fusible metal.

6. A time delay fuse comprising an electrically conductive elongated single piece fuse element formed from a sheet of fusible metal having a predetermined relatively high melting point and having between its ends a pair of spaced apart substantially tubular parts forming a pair of spaced apart receptacle portions, a part of limited cross sectional area extending between the tubular parts and forming a resistance heating portion adjacent to and between the receptacle portions, and a tab of limited cross sectional area extending from the outer end of each tubular part and each forming a resistance heating portion at and adjacent to the outer end of each receptacle portion, a body of fusible metal having a predetermined relatively low melting point and secured in each receptacle portion

of the fuse element in intimate contact therewith by dipping the fuse element in a molten pool of said lower melting point fusible metal so as to provide high thermal conductivity between the two.

5 to the ends of the fuse element for incorporating the same in an electric circuit to be protected, a sustained overload in the electric circuit causing the resistance heating portions of the fuse element to heat the fuse element and the bodies of fusible metal substantially as a unit, and

10 the heating of the resistance portions of the fuse element to the relatively high melting point thereof for breaking the electric circuit being delayed by the specific heat and latent heat of fusion of the bodies of the relatively low melting point fusible metal.

- 15 7. A time delay fuse comprising an electrically conductive single piece fuse element formed from a fusible metal having a predetermined relatively high melting point and having between its ends a substantially tubular receptacle portion and a resistance heating portion of limited cross
- 20 sectional area at each end of and adjacent to the receptacle portion, a body of fusible metal having a predetermined relatively low melting point and secured in the receptacle portion of the fuse element in intimate contact therewith so as to provide high thermal conductivity therebetween,
- 25 and electrical terminals connected to the ends of the fuse element for incorporating the same in an electric circuit to be protected, a sustained overload in the electric circuit causing the resistance heating portion of the fuse element to heat the fuse element and the body of fusible
- 30 metal substantially as a unit, and the heating of the receptacle heating portions of the fuse element to the relatively high melting point thereof for breaking the electric circuit being delayed by the specific heat and the latent heat of fusion of the body of the relatively low
- 35 melting point fusible metal.

8. A time delay fuse comprising an electrically conductive single piece fuse element formed from a fusible metal having a predetermined relatively high melting point and having between its ends a substantially tubular receptacle portion and a resistance heating portion of limited cross sectional area at each end of and adjacent to the receptacle portion, a body of fusible metal having a predetermined relatively low melting point and secured in the receptacle portion of the fuse element in intimate contact therewith 40 by dipping the fuse element in a molten pool of said lower melting point fusible metal so as to provide high thermal conductivity therebetween, and electrical terminals connected to the ends of the fuse element for incorporating the same in an electric circuit to be protected, a sustained 45 overload in the electric circuit causing the resistance heating portion of the fuse element to heat the fuse element and the body of fusible metal substantially as a unit, and the heating of the receptacle heating portions of the fuse element to the relatively high melting point thereof for breaking 50 the electric circuit being delayed by the specific heat and the latent heat of fusion of the body of the relatively 55 low melting point fusible metal.

9. A time delay fuse comprising an electrically conductive elongated single piece fuse element formed from a fusible metal having a predetermined relatively high melting point and having between its ends a pair of spaced apart substantially tubular receptacle portions, a resistance heating portion of limited cross sectional area adjacent to and between the receptacle portions and a resistance heating portion at and adjacent to the outer end of each receptacle portion, a body of fusible metal having a predetermined relatively low melting point and secured in each receptacle portion of the fuse element in intimate contact therewith so as to provide high thermal conductivity therebetween, and electrical terminals connected to the ends of the fuse element for incorporating the same in an electric circuit to be protected, a sustained overload in the electric circuit causing the resistance heating portions of the fuse element to heat the fuse element and the bodies of fusible metal substantially as a unit, and the

heating of the resistance heating portions of the fuse element to the relatively high melting point thereof for breaking the electric circuit being delayed by the specific heat and latent heat of fusion of the bodies of the relatively low melting point fusible metal.

10. A time delay fuse comprising an electrically conductive elongated single piece fuse element formed from a fusible metal having a predetermined relatively high melting point and having between its ends a pair of spaced apart substantially tubular receptacle portions, a resistance heating portion of limited cross sectional area adjacent to and between the receptacle portions and a resistance heating portion at and adjacent to the outer end of each receptacle portion, a body of fusible metal having a predetermined relatively low melting point and in intimate contact therewith by dipping the fuse element in a molten pool of said lower melting point fusible metal so as to provide high thermal conductivity therebetween, and electrical terminals connected to the ends of the fuse element for incorporating the same in an electric circuit to be protected, a sustained overload in the electric circuit causing the resistance heating portions of the fuse element to heat the fuse element and the bodies of fusible metal substantially as a unit, and the heating of the resistance heating portions of the fuse element to the relatively high melting point thereof for breaking the electric circuit being delayed by the specific heat and latent heat of fusion of the bodies of the relatively low melting point fusible metal.

11. A time delay fuse comprising an electrically conductive elongated single piece fuse element formed from a fusible metal having a predetermined relatively high melting point and having between its ends a substantially tubular receptacle portion and a resistance heating portion of limited cross sectional area at each end of and adjacent to the receptacle portion, a body of fusible metal having a predetermined relatively low melting point and secured in the receptacle portion of the fuse element in intimate contact therewith so as to provide high thermal conductivity therebetween, a tubular closure of electrical insulating material for the fuse element, electrically conductive caps secured to the ends of the tubular closure and forming electrical terminals for connecting the fuse in an electric circuit to be protected, means for electrically connecting the ends of the fuse element to the caps, said resistance heating portions of the fuse element being bent substantially normal to the axis of the tubular receptacle portion adjacent the ends thereof to compensate for thermal expansion and contraction, a sustained overload in the electric circuit causing the resistance heating portions of the fuse element to heat the fuse element and the body of fusible metal substantially as a unit, and the heating of the resistance heating portions of the fuse element to the relatively high melting point thereof for breaking the electric circuit being delayed by the specific heat and the latent heat of fusion of the body of the relatively low melting point fusible metal.

12. A time delay fuse comprising an electrically conductive elongated single piece fuse element formed from a fusible metal having a predetermined relatively high melting point and having between its ends a pair of spaced apart substantially tubular receptacle portions, an inner resistance heating portion of limited cross sectional area adjacent to and between the receptacle portions and an outer resistance heating portion of limited cross sectional area at and adjacent to the outer ends of each receptacle portion, a body of fusible metal having a predetermined relatively low melting point and secured in each receptacle portion of the fuse element in intimate contact therewith so as to provide high thermal conductivity therebetween, a tubular closure of electrical insulating material for the fuse element, electrically conductive caps secured to the ends of the tubular closure and forming electrical terminals for connecting the fuse in an electric circuit to be protected, means for electrically connecting the ends of

the fuse element to the caps, said outer resistance heating portions of the fuse element being bent substantially normal to the axis of the tubular receptacle portions adjacent the outer ends thereof to compensate for thermal expansion and contraction, a sustained overload in the electric circuit causing the resistance heating portions of the fuse element to heat the fuse element and the bodies of fusible metal substantially as a unit, and the heating of the resistance heating portions of the fuse element to

5 the relatively high melting point thereof for breaking the electric circuit being delayed by the specific heat and latent heat of fusion of the bodies of the relatively low melting point fusible metal.

13. A time delay fuse comprising an electrically conductive elongated single piece fuse element formed from a sheet of fusible metal having a predetermined relatively high melting point and having between its ends a substantially tubular part forming a receptacle portion and a tab of limited cross sectional area extending from each end

20 of the tubular part and each forming a resistance heating portion adjacent to the receptacle portion, a body of fusible metal having a predetermined relatively low melting point and secured in the receptacle portion of the fuse element in intimate contact therewith so as to provide high thermal conductivity therebetween, a tubular closure of electrical insulating material for the fuse element, electrically conductive caps secured to the ends of the tubular closure and forming electrical terminals for connecting the fuse in an electric circuit to be protected, means for

30 electrically connecting the ends of the fuse element to the caps, said resistance heating portions of the fuse element being bent substantially normal to the axis of the tubular receptacle portion adjacent the ends thereof to compensate for thermal expansion and contraction, a sustained overload in the electric circuit causing the resistance heating portions of the fuse element to heat the fuse element and the body of fusible metal substantially as a unit, and the heating of the resistance heating portions of the fuse element to the relatively high melting point thereof for

35 breaking the electric circuit being delayed by the specific heat and the latent heat of fusion of the body of the relatively low melting point fusible metal.

14. A time delay fuse comprising an electrically conductive elongated single piece fuse element formed from a sheet of fusible metal having a predetermined relatively

45 high melting point and having between its ends a pair of spaced apart substantially tubular parts forming a pair of spaced apart receptacle portions, a part of limited cross sectional area extending between the tubular parts and forming a resistance heating portion adjacent to and be-

50 tween the receptacle portions, and a tab of limited cross sectional area extending from the outer end of each tubular part and each forming a resistance heating portion at and adjacent to the outer end of each receptacle portion, a body of fusible metal having a predetermined relatively

55 low melting point and secured in each receptacle portion of the fuse element in intimate contact therewith, a tubular closure of electrical insulating material for the fuse element, electrically conductive caps secured to the ends of the tubular closure and forming electrical terminals for

60 connecting the fuse in an electric circuit to be protected, means for electrically connecting the ends of the fuse element to the caps, said outer resistance heating portions of the fuse element being bent substantially normal to the axis of the tubular receptacle portions adjacent the outer

65 ends thereof to compensate for thermal expansion and contraction, a sustained overload in the electric circuit causing the resistance heating portions of the fuse element to heat the fuse element and the bodies of fusible metal substantially as a unit, and the heating of the resistance

70 heating portions of the fuse element to the relatively high melting point thereof for breaking the electric circuit being delayed by the specific heat and latent heat of fusion of the bodies of the relatively low melting point fusible metal.
